ADAPTER FOR LOW-FREQUENCY
AMPLIFIERS

Pieter Frederik van Eldik, Eindhoven, Netherlands, assignor, by mesne assignments, to Radio Corporation of America, New York, N. Y., a corporation of Delaware

Application November 13, 1937, Serial No. 174,315
In Germany December 28, 1936

2 Claims. (Cl. 179—100.11)

This invention relates to a pre-connected apparatus for low frequency amplifiers by means of which different devices producing or conducting audio-frequency oscillations can be connected by means of a change-over switch, the condition having to be satisfied that these devices are adapted to the input circuit of the amplifier.

It is known to use a low frequency transformer for each of the devices which produce or conduct audio-frequency oscillations and to which the amplifier is to be connected. These transformers are given such a size that correct adaptation is ensured for all devices.

The invention consists in providing a low frequency transformer designed for the adaptation and common to all devices, whereas impedances, preferably resistances, are provided for adaptation of the said devices or part thereof to the transformer. Thus the advantage is obtained that the device is extremely simple and cheap.

The drawing represents one form of construction of an apparatus according to the invention. The apparatus comprises a low frequency transformer 1 whose secondary winding can be connected, through a change-over switch described hereinafter, to the terminals 2 for connecting the amplifier. The secondary winding is bridged by a potentiometer-resistance 3 part of which can be short-circuited by means of a contact 4 and which serves for the volume control. In addition the apparatus comprises terminal pairs 5, 6, 7 and 9 for connecting the different devices producing or conducting oscillations. The terminals 5 are provided for connecting a radio set.

For achieving correct adaptation these terminals are bridged by a resistance 10 and the voltage to be amplified is derived from a small part of this resistance. This voltage is supplied to the primary transformer winding through the mutually coupled switches 12 and 13.

The terminals 6 are provided for connecting a transmission line, for instance, a telephone line. In this case, also, only a small part of the available voltage is supplied to the primary transformer winding. For this purpose a resistance 11 of which points symmetrically placed with respect to the middle are connected to the switch contacts in parallel with the said terminals. If desired, the middle of the resistance 11 may be earthed. When the switch 12, 13 bears on the said contacts connected to the resistance 11 the device is adapted for the connection of a telephone line. In this manner the telephone line remains entirely symmetrical in electrical respect.

A third pair of terminals 7 is provided for connecting a microphone. It is presumed that this microphone is adapted without using separate adapting resistances. The low frequency transformer may be given such a size that suitable adaptation is obtained for this case without using separate impedances. The feed current for the microphone is derived from the terminals 8 one of which is connected to a third switch lever 14 mechanically coupled to the two first-mentioned switch levers 12 and 13. It will be obvious that when the switch levers bear on the fourth contact of each series of contacts the apparatus is adapted for the reproduction of microphone currents.

In addition the said switch has a position of rest wherein the primary transformer winding is connected to none of the pairs of terminals. This applies when the switch levers bear on the second contact of each series.

The above devices permit several apparatus to be connected to a low frequency amplifier by means of a single low frequency transformer. The fifth pair of terminals 9 serves for connecting a pick-up, in which case a low frequency transformer can be dispensed with. Consequently these terminals are directly connected to the terminals 2 through a switch 15 which has also five positions and is coupled to the said switches. In this case volume control is not necessary since this is in general directly provided on the pick-up. In the position of rest of the switch the terminals 2 are short-circuited.

What I claim is:

1. In low frequency amplifying apparatus, a plurality of individual lines each including means for connection thereof to a different source of energy to be amplified, a pair of terminals adapted to be connected to the input of an amplifier, a coupling transformer including a primary winding and a secondary winding, said secondary winding being connected across said pair of terminals, individual impedances connected across each of said lines, selective switching means interposed between the primary winding and said lines for connecting the primary winding across portions of any one of said impedances, said portions being arranged so that impedance match is obtained between each of the lines and the transformer, said switching means comprising a plurality of uni-controlled switches each having a plurality of contact points determined by the number of individual lines arranged to be connected to the transformer primary and a blank contact position wherein the primary of the

transformer winding is left open and the secondary of the transformer is short-circuited.

2. In low frequency amplifying apparatus, a plurality of individual lines each including means for connection thereof to a different source of energy to be amplified, a pair of terminals adapted to be connected to the input of an amplifier, a coupling transformer including a primary winding and a secondary winding, said secondary winding being connected across said pair of terminals, individual impedances connected across each of said lines, selective switching means interposed between the primary winding and said lines for connecting the primary winding across portions of any one of said impedances, said por-

tions being arranged so that impedance match is obtained between each of the lines and the transformer, said switching means comprising a plurality of uni-control switches each having a plurality of contact points determined by the number of individual lines arranged to be connected to the transformer primary, a blank contact position wherein the primary of the transformer winding is left open and the secondary of the transformer is short-circuited, and an additional position wherein one of said lines is connected directly across the first named pair of terminals.

PIETER FREDERIK VAN ELDIK.
